STARTER FOR INTERNAL COMBUSTION ENGINES

Wayne C. Criley, Kansas City, Mo.

Application March 31, 1938, Serial No. 199,313

6 Claims. (Cl. 123—179)

My invention relates to a starter for internal combustion engines and more particularly to a light, hydro-pneumatic starter adapted for use in starting airplane motors, outboard motors, 5 light Diesel engines and other internal combustion engines.

Small airplanes cannot be equipped with the customary electric motor driven starters, operated from a storage battery as the weight of the 10 assembly is too great, the storage battery alone being far in excess of the permissible weight. It will be readily appreciated that, in light airplanes, weight is an important factor, so much so that light airplanes are universally started by hand, 15 usually by rotating a propeller. This is a dangerous procedure and frequently results in a loss of limb. Outboard motors, likewise have not been provided with mechanical starters and resort must be had to hand starters. Women have difficulty 20 in starting outboard motors and especially those of the multi-cylinder type.

One object of my invention is to provide a compact, light weight starter for internal combustion engines.

Another object of my invention is to provide a starting arrangement for internal combustion engines which may, due to its small size and light weight, be applied to airplane engines.

Other and further objects of my invention will 30 appear from the following description.

In the accompanying drawing which forms part of the instant specification and is to be read in conjunction therewith and in which like reference numerals are used to indicate like parts in the various views;

Figure 1 is a top plan view of my starting assembly.

Figure 2 is an elevation of my starting assembly with parts broken away.

Figure 3 is a section, taken on a line 3—3 of Figure 1.

Figure 4 is a sectional view taken on a line 4—4 of Figure 2.

Figure 5 is an enlarged, fragmentary view, with parts in section, of the automatic tripping cylinder.

In general, my invention contemplates an arrangement whereby comparatively high pneumatic pressures may be built up with comparatively 50 small mechanical motion, and the provision of means for rotating the crank shaft of the engine to be started.

More particularly, referring now to the drawing, a compressor cylinder 1 is provided with a piston 2 adapted to be moved by a screw 3, op-

erated in suitable threads formed in the cylinder head 4 by operating handle 5. A pipe 6 communicates with the starter cylinder 7 in which is positioned a starter piston 8 adapted to reciprocate a rack 9. The rack 9 is adapted to engage a pinion 10, keyed to a sleeve 11 by key 12. The sleeve 11 is mounted upon a shaft 13 and is adapted to move axially thereof. The other end of the sleeve 11 carries complementary member 14 of a clutch. The other complementary member 15 of the clutch is secured by any suitable means to the fly wheel 16 or other suitable part of the motor to be started. The fly wheel 16 is secured to the crank shaft 17 of the motor to be started. The rack 9 is provided with a groove 18 in its under side, the groove riding upon a guide wheel 19 adapted to rotate upon a shaft 20 on suitable ball bearings 21. A spring 22 tends to urge the piston 8 to the left, as viewed in Figure 3. A detent 23 is adapted to seat in a notch 24 formed in the rack and prevent the rack from moving to the right, as viewed in Figure 3. The detent 23 is formed on a rotatable shaft 25 which projects through the housing 26. The starter cylinder 7 communicates with the booster cylinder 27 through a pipe 28. A piston 29 is lodged in the booster cylinder 27. The pipes 6 and 28, the space to the right of piston 29 within the compressor cylinder 1, the space to the left of piston 8 of starter cylinder 7, and the space to the left of piston 29 in the booster cylinder 27 are completely filled with any suitable liquid such as a mixture of glycerine and water or glycerine and alcohol, if desired, oil.

The booster cylinder 27 is formed with an end 35 provided with an opening 31 adapted to be closed by a check valve 32 and a cap 33. Communicating with pipe 6 is a branch pipe 34 leading to an automatic tripping cylinder 35 in which is housed a piston 36 having a piston rod 37. A spring 38 normally urges the piston 36 to the left as viewed in Figure 5. The space to the left of piston 36 and pipe 34 is completely filled with liquid. The outer end of the groove 18 formed in rack 9 is provided with a reentrant portion 39 bridged by a flat spring 40.

The outer portion of shaft 25 which is rotatably mounted in housing 26 is provided with an operating lever 41. A spring 42 tends to rotate the shaft 25 in a clockwise direction, as viewed in Figures 2 and 3, thus holding the detent 23 in the notch 24. A shaft 43 is rotatably mounted in the upper end of the housing 26 and extends upwardly out of the housing. The lower end of the shaft 43 carries an arm 44 adapted to engage the pinion 55

10. A lever 45 is keyed to the shaft 43, as can readily be seen by reference to Figure 1. Rotation of the shaft 43 clockwise causes the arm 44 to move the pinion 10, together with sleeve 11 and clutch member 14 to the left, as viewed in Figure 4, thus engaging the clutch members. The upper end 46 of starting operating lever 41 is positioned adjacent the lever 45 so that the clockwise rotation of the lever 45 will engage the upper end 46 of the arm 41, rotating the shaft 25 in a clockwise direction and moving the detent 23 out of the notch 24. One end of the lever 45 is connected to piston rod 37. The other end of lever 45 is connected to a cable 47.
15. It will be apparent to those skilled in the art that, if the device is to be small in size, the area of the starting piston 8 which actuates the starting rack 9 would have to be small. If the starting rack, with the clutch members engaged and the pinion 10 in mesh with the teeth of the rack 9, is to move, it must rotate the crank shaft and move the associated motor pistons of the motor to be started. It must move one or more pistons of the motor through compression and, in an airplane motor, for example, high compression ratios are frequently used. It will be further obvious that, since we have only a small starting piston area to deal with, that high pressures must be employed so that the product of the area of the starting piston times the pressure acting upon it times the mechanical advantage of the rack and pinion will be greater than the area of a piston of the motor to be started times the pressure existing within the motor cylinder at the point of compression plus the response to movement of the associated parts, caused by friction.
20. It will be further obvious that, if this high pressure is to be achieved solely by the movement of compressor piston 2 acting upon air at atmospheric pressure, that the stroke of the compressor piston must be great if a single stroke is to be used. If the compressor piston is to be reciprocated, using only air, a check valve will have to be positioned at the outlet of the compressor cylinder and a number of strokes of the compressor piston will have to be made. The first premise, namely the use of one long stroke, would involve a compressor cylinder of such length that the advantages aimed at, namely lightness and weight would be sacrificed to say nothing of the space required. Then, too, a long stroke would be time consuming and would render the device commercially impractical. The time consuming 25 operation of a long stroke would also be present if the compressor piston were reciprocated a number of times to obtain the equivalent of one long stroke.
25. I overcome the disadvantages above pointed out by, with the parts in the position shown in Figure 2, filling the booster cylinder 27 to the right of piston 28 with compressed air. The cap 33 is removed and a source of compressed air connected to the end 38. Compressed air fills the cylinder 27, flowing thereto through passageway 31, being prevented from escaping by check valve 32. During this operation, the piston 28 is at the extreme left of the cylinder 27, seated upon a seat 48 formed on cylinder head 49. The piston 28 thus acts as a valve. Air or other suitable compressible fluid under pressure which may vary from 150 pounds per square inch to 250 pounds per square inch or higher is thus charged to the booster cylinder 27.
30. When the piston 2 is moved from the position

shown in Figure 2 to the position shown in Figure 3, it will displace the fluid to the right of piston 2 within cylinder 1. The fluid acting against piston 8 of the starter cylinder cannot move, since the detent 23 holds the rack 9 which is secured to the piston 8 from moving. The liquid therefore displaces the piston 28 of the booster cylinder 27, further compressing the already compressed air. At the same time, the liquid being displaced will act upon piston 36 resisted by spring 38. The area of piston 36 and spring 38 is such that it will not move until the desired starting pressure is approached. The compressing of the already compressed air within the booster cylinder 27 creates an extremely high pressure as will be readily apparent. In this manner, the desired high starting pressure which may vary, depending upon the motor to be started, from 500 pounds per square inch to 1200 pounds per square inch or higher, is readily achieved with a single stroke of the compressor piston. The pressure exerted by the compressed gas behind piston 28 is exerted by hydrostatic pressure upon starting piston 8. When the desired high pressure is ultimately reached, piston 36 will have moved to the right against the action of spring 38 under the hydrostatic pressure generated. The movement of piston rod 37 to the right rotates the lever 45 and associated shaft 43 in a clockwise direction. Rotation of shaft 43 moves the pinion 10 into engaging position. If the teeth of the pinion are not lined up with the teeth of the rack, the rack will be depressed by flexing of spring 40, thus insuring engagement of the teeth of the pinion with the teeth of the rack. At the same time, the clutch members 14 and 15 will be engaged. At the same time, one end of the lever 45 will have engaged the upper end 46 of the operating lever 41 and further motion will rotate the shaft 25, moving the detent 23 out of the notch 24. When the detent is free of the notch, the rack will move to the right under the influence of the pressure stored in booster cylinder 27, starting the engine. When the pressure is released, the spring 38 will move 30 counter-clockwise and permitting the clutch to disengage and the pinion 10 to disengage the rack. The operating handle 5 is then operated to retract the piston 2 permitting the piston 22 to move the rack and piston 8 to the left. When the notch 24 is opposite the detent 23, the spring 42 will rotate the shaft 25 to bring the detent into the notch and the parts will be in the position shown in Figure 2. When it is again desired 35 to start the motor, the operating handle 5 is rotated and the operation repeated.

If desired, the automatic tripping piston may be removed or the piston rod 37 disconnected. In such case, the arrangement may be operated 40 through a cable 47 connected to arm 45, the end of the cable being positioned in the cockpit or other suitable place, as desired.

It will be observed that I have accomplished the objects of my invention. I have provided a small starter adapted to start airplane motors, which is light in weight. A starter, according to my invention, has been used on a well known, light airplane and weighs less than 5 pounds.

It will be understood that certain features and 45 sub-combinations are of utility and may be employed without reference to other features and sub-combinations. This is contemplated by and is within the scope of my claims. It is further obvious that various changes may be made in de- 50

tails within the scope of my claims without departing from the spirit of my invention. It is, therefore, to be understood that my invention is not to be limited to the specific details shown and 5 described.

Having thus described my invention, what I claim is:

1. A starter for internal combustion engines, including in combination a starter cylinder, a piston 10 ton in said cylinder, means responsive to the movement of said piston for cranking an internal combustion engine, a detent for selectively preventing movement of said piston, a booster cylinder, a piston in said booster cylinder, means providing communication between said booster cylinder and said starter cylinder, a pump cylinder, a piston in said pump cylinder, means providing communication between said pump cylinder and said starter cylinder, liquid disposed in said pump 15 cylinder, said starter cylinder and said inter-communicating means, said booster cylinder being filled with a gas under superatmospheric pressure, the construction being such that, with said detent in starter piston immobilizing position, movement of said pump piston in pumping direction will pump said liquid into said booster cylinder, displacing the booster cylinder piston to further compress the gas disposed therein, whereby when said detent is moved to free said 20 starter piston, the pressure thus built up is free to move the starter piston to crank the internal combustion engine to be started.

2. In a starter for internal combustion engines having a starter cylinder, a piston within said 25 starter cylinder adapted to be reciprocated therein, means actuated by the reciprocation of the starter piston for cranking an internal combustion engine, a booster cylinder having a booster piston disposed therein, means providing communication between said starter cylinder and said booster cylinder, a liquid pump having a discharge port, means providing communication between said pump discharge port and said starter cylinder, the combination comprising gas under pressure disposed within said booster cylinder on one 30 side of said booster piston, said communicating means providing communication between the other side of said booster piston and said starter cylinder, said communicating means, said starter 35 cylinder

cylinder on one side of the starter piston and the means providing communication between the liquid pump and the starter cylinder being liquid-ful, and means for temporarily immobilizing the starter piston, the construction being such that, when said liquid pump is operated, liquid will be pumped into the booster cylinder to move said booster piston to further compress the compressed gas disposed therein, whereby, when a desired pressure is reached, the starter piston 10 immobilizing means may be operated to release the starter piston to crank the internal combustion engine to be started.

3. A starter as in claim 2, wherein said means actuated by reciprocation of the starter piston for cranking the internal combustion engine comprises a rack, a pinion adapted to be rotated by said rack, and means actuated by the rotation of said pinion for rotating the crank shaft of an internal combustion engine.

4. A starter as in claim 2, wherein said means actuated by reciprocation of the starter piston for cranking the internal combustion engine comprises a rack, a pinion adapted to be rotated by said rack, a sleeve, said pinion being carried by said sleeve normally out of engagement with said rack, a clutch member carried by said sleeve, a complementary clutch member carried by the crank shaft of the engine to be started, the construction being such that, when said pinion is moved into rack engaging position, said clutch members will engage so that rotation of said pinion by said rack will crank the internal combustion engine to be started.

5. A starter as in claim 1 in which said means responsive to the movement of said starter piston for cranking the internal combustion engine comprises a rack, a pinion normally out of engagement with said rack, a sleeve, said pinion being carried by said sleeve, a clutch member carried by said sleeve, a complementary clutch member carried by the crank shaft of the engine to be started, and fluid pressure means for moving said pinion into rack engaging position and for engaging said complementary clutch members.

6. A starter as in claim 1, including in combination fluid pressure means for moving said detent to starter piston releasing position.

WAYNE C. CRILEY.
